(57) **CLAIM**

The ornamental design for a cleaning foot of a multi-surface vacuum cleaner, as shown and described.

DESCRIPTION

FIG. 1 is a front perspective view of first embodiment of a cleaning foot of a multi-surface vacuum cleaner showing our new design;

FIG. 2 is a front view thereof;

FIG. 3 is a left side view thereof;

FIG. 4 is a right side view thereof; and,

FIG. 5 is a top view thereof.

The details shown in broken lines form no part of the claimed design.
